SAFETY-STOP FOR VEHICLES.

1,237,261.

Specification of Letters Patent. Patented Aug. 14, 1917.

Application filed December 30, 1915. Serial No. 69,508.

To all whom it may concern:

Be it known that I, JAMES MICHAEL CUNNEEN, a citizen of the United States, and resident of Jersey City, in the county of Hudson and State of New Jersey, have invented a certain new and useful Safety-Stop for Vehicles, of which the following is a specification.

This invention consists of what may properly be termed a disappearing stop or abutment, adapted to be placed in the path of a vehicle so as to hold the latter temporarily in a fixed or predetermined position.

The principal object of the invention is to provide a simple and convenient means whereby one or more vehicles can be held safely at a certain spot or within a given space, while located upon or transferred with a movable structure, such as the platform of a lift, the deck of a ferry-boat, the floor of a drawbridge, or the like, even though subjected meanwhile to gravitating forces, concussive strains, or misdirected impulses. It is understood that by preventing the vehicles from being unduly shifted, rolled, slid, or otherwise moved out of their assigned places in or upon the structures referred to, it will be possible henceforth to avoid numerous accidents, which in the past have been attended with loss of life, the maiming of limbs, and destruction of property.

Another object, correlated to the above, is the provision of an actuating mechanism for the stop, so connected or associated with the operation of the structure carrying the vehicle, that it will be impossible to impart movement to the structure before the stop has been elevated for safeguarding the vehicle thereon, and conversely, to remove the stop and liberate the vehicle prior to the structure being brought to a standstill. Accidents that would result from some premature attempt to place a vehicle aboard a moving structure, or from ill-timed removal of the former from the latter, are thereby prevented.

An additional object, similarly deducible from the foregoing, is to afford a check upon the faithfulness and efficiency of the attendant in charge, by so locating and arranging the stop-operating mechanism that it will be under his immediate command, and he therefore may have sole control over both the application of the stop to the ve-

hicle and the starting of the movable structure, without risk or fear of anyone else interfering with the same. Thus, it will be practicable to center and fix upon a single person the full responsibility for the judicious handling of the stop, the vehicle, and the structure.

Other objects and advantages of the invention will in part be obvious, and in part be set forth while specifying the various features of construction and operation hereinafter contained.

Referring to the drawings hereto annexed, for a detailed description of the invention,—

Figure 1 is a sectional side elevation, 70 showing part of a freight elevator to which the invention is applied;

Fig. 2 is an end view of the same, looking from the right-hand side of Fig. 1;

Fig. 3 is a sectional plan taken on the 75 line 3—3 of Fig. 1, looking downward, as indicated by the arrow; and

Fig. 4 is a fragmentary sectional elevation of a modified form of the invention.

In these several views, the numeral 11 80 designates an elevator platform, which may be of any approved construction, such, for instance, as it is found convenient to use in main post-offices, and in buildings of large express companies, for raising or lowering trucks loaded with mail-bags or parcels, from one floor to another. As shown in Figs. 1 to 3, this platform may constitute the floor of a car provided with side walls, as 12, 13, but the latter are not indispensable, 90 since there is no occasion, really, to place safeguards about the trucks in a lateral direction.

The power employed to run the elevator car or platform may be of any preferred 95 kind, and likewise the hoisting mechanism. For purposes of illustration, the annexed drawings represent a conventional species of hydraulic elevator attachment, including a rope 14, wound partly upon a drum 15, and 100 operated alternately to open and close a water-valve (not shown). As seen in Fig. 2, the rope 14 is led the required distance above and below the car by means of pulleys or sheaves 17, 18, and traverses the platform within reach of the operator in the usual manner, passing also through a length of tubing 19, to which further reference will be made hereinafter.

Transverse grooves 21, 22 are provided in 110

the surface of the floor or platform 11. These grooves are designed to contain a pair of disappearing stops 23, 24, in such a manner that the platform's surface can be rendered practically even and smooth, owing to the disappearance of the stops, when it is desired to place a truck in the elevator or remove it therefrom as the case may be, the condition of the surface then admitting of 10 the truck being rolled on or off without unusual exertion. But, whenever the platform is to be raised or lowered, the stops are caused to rise from its surface so as to stand in the way of the truck thereon and 15 keep it from moving either forward or backward, the distance between the stops being suitably proportioned to the length of space occupied by the truck wheels (or runners) measured in a fore-and-aft direction. Fig. 20 1 of the accompanying drawings shows one stop (23) leveled, and the other stop (24) elevated, the raised position of the former being also indicated by dotted lines.

Preferably, the stops 23, 24 are made each 25 of a metal bar shaped to fit either of the grooves 21, 22, and flat-faced so that as the bar lies down in its groove it will be approximately flush with the adjoining surface of the floor 11, and offer no appreciable 30 resistance to a truck passing over and across it in either direction. However, when turned on edge, the bar is of sufficient width and thickness to block the way of the truck, either in front or rear.

35 It is understood that when a truck is moved onto the platform, the inner or remote stop thereon is first raised, for example, the bar 24 in Figs. 1 and 3, while the other stop or bar, as 23, is kept down. By 40 so doing, the truck may be pushed, pulled, or driven swiftly over and across the sub-lying nearer bar, and will be safely arrested in its forward movement, by the raised bar ahead, if perchance there is a 45 slight miscalculation of the effort or energy required to have it reach its resting place on the platform. As soon as the front stop has been touched or approached sufficiently 50 near by the truck, the rear stop is in turn elevated, and the pair of stops then operates to resist the truck's tendency, if any, either to advance or to recede. The order followed 55 in manipulating the stops, as here explained, may be reversed or not, for the purpose of taking the truck off the platform, depend- 60 ing on the direction in which the truck is to be removed.

The bars constituting the stops 23, 24 aforesaid are conveniently connected to the 65 platform 11 by means of hinge pins 26, 27, projecting outwardly from their opposite ends and fitted to rock in side bearings, as at 28, 29. As shown, these pins and bearings may be located within the grooves 21, 65 22, at the outer edges of the bars, so that the

latter with their respective hinges will appear to be countersunk in the platform's surface while in their downward position, and when the bars are raised, only the inner edges and other free portions thereof will stand outside of the grooves, the hinged parts remaining inside or below the surface always.

In order to regulate the movement of the said stops, when raised out of the said 75 grooves, their opposite ends are bent up, each at a right angle, as at 31, 32, in such a manner that as the stops are being turned on edge, the angular extremities thereof (like 32 in Figs. 1 to 3) will contact with 80 the adjacent surface of the platform, and by bearing thereon, will prevent the stops from being forced out too far either forward or rearward. The movement of each stop is thus limited to an arc never exceeding ninety 85 degrees,—thereby insuring what is deemed to be the best operative position for either stop in the form of the invention herein exemplified.

Levers 35 and 36 are provided to operate 90 the stops 23 and 24, preferably one at a time, that is, separately and independently one of the other. These levers have been shown as fulcrumed in superposed relation and intermediate of their lengths, at 37, 38, Figs. 1 95 and 3, in an offset portion 39 of the before mentioned tubing 19, which affords them a convenient support, within reach of the person whose duty it is to direct the alternate movements of either the truck or the platform, or of both truck and platform. According to the arrangement adopted, the upper lever 35 governs the movements of the outer stop 23, by connections including a pair of oppositely-disposed bell-crank 41, 42, supported from hangers 43, 44, fastened to the underside of the platform 11, and rods or links 45, 46, and 47, pivotally joining the said bell-crank to each other, and to the lever and stop respectively. In a similar 100 manner, the lower lever 36 is operatively connected to the inner stop 24, by means of oppositely-arranged bell-crank 50, 51, attached to the hanger 43, and intermediate rods or links 52, 53, and 54. As will be 105 noted, the arrangement in both instances is such that a downward movement of either lever will cause a like movement of the stop thereto connected, and reversely, an upward move of the lever brings about a corresponding move of the stop, as clearly indicated in the drawings. The operative connections for the pair of stops are respectively attached to the right and left of their respective levers, in order that the latter may conveniently be superposed for manipulation in a same vertical plane, to wit, the plane of the tube 19, through which the valve-actuating rope 14 is passed.

The control of the water-valve aforesaid 130

is subordinated to the working of the pair of stops 23, 24, through adaptation of the levers 35, 36, to the function of gripping and releasing, alternately, the rope 14 which opens and closes the said valve. This is effected by centering the levers endwise with relation to the rope, that is, the part thereof which runs through the tube 19. To that end, the rope is brought down from one of the pulleys 18, and led into the tube 19, through an opening 57, in a cap 58 covering the same. There the rope is received in a vertical guideway 59, provided interiorly of the tube, in alinement with the said opening, and diametrically opposite the offset 39, wherein the levers are fulcrumed. The inner ends of the levers are chamfered, as at 60, and arranged to oscillate in the guideway 59, so that when either lever, 35 or 36, is placed in a horizontal position, its inner extremity will reach the rope within the guideway and press it against the opposite wall of the tube, thus operating to grip the rope tightly and keep it from further actuating the water-valve, the latter being then normally closed. But, if the outer end of the lever be raised, the chamfered inner end thereof will recede from the rope and release it. To increase the gripping action on the rope, ledges 61, 62, 63, are placed across the guideway 39, above, between, and below the inner ends of the levers oscillating therein. These ledges are positioned so as to receive between them the bights of the rope that are pressed upon by the inner extremities of the two levers, in the manner indicated, for example, at 64 in Fig. 1, and they coact with the levers and the tube wall in maintaining the rope stationary, owing to added points of friction. With the aid of the said ledges, and proper adjustment, either or both of the levers will hold the rope fast whenever and as long as required, sufficiently to preclude the shifting thereof by any person other than the one authorized to operate the levers on the platform.

In case electric power is utilized, instead of the hydraulic, to work the elevator car or platform, the operation thereof can still be rendered secondary in point of time to the placing of the stops, or either of them, in a predetermined position. Then, the levers controlling the stops may be put into the electric circuit of the elevator, and functioned to make or break the circuit, as needed to enable either stop to be raised or lowered in season. An arrangement of this nature is exemplified in Fig. 4, which as before stated represents a modified embodiment of the invention. As the latter-named figure shows, the electric circuit includes wires 67, 68, entering the tube 19 from the opposite ends thereof and respectively attached to binding-posts 69, 70, on the tube wall that faces the extension 39, in which

are mounted the levers 35, 36. Between the posts 69, 70, are two switches, interconnected by a wire 71, and comprising each a fixed contact 72, secured to the said tube wall, and a coacting movable contact 73, carried by a leaf-spring 74. The contacts 73 are normally disengaged from the contacts 72 by the springs 74, but the latter are located in the plane of oscillation of the levers 35, 36, so that as either lever is operated to raise the stop controlled thereby, its inner end will meet one of the springs and serve to close one of the switches, by bringing the corresponding contacts together. If the lever is swung in a contrary direction, to lower the stop which it controls, its inner end moves away from the leaf-spring, and the switch is opened. Fig. 4 represents one switch as being open, and the other closed. The two switches, it will be observed, must be closed in order to complete the electric circuit, and therefore it follows that the elevator car or platform will neither ascend nor descend until both levers have been oscillated in the same manner, that is, operated to force the leaf-springs 74, with their movable contacts 73, against the stationary contacts 72, in which case the stops 23, 24 are assumed to be in the requisite position to permit moving the car or platform safely, with or without a vehicle on it.

Each one of the levers 35, 36 is provided with a lock to keep it in the position which it should retain, after being swung up or down to raise or lower the stops 23, 24. This lock includes a dog or toothed projection 77, which projects from a sleeve 78, slidably upon the outer end of the lever (35 or 36) and is adapted to engage a notched plate 79, secured to one side of the offset 39 on the tube 19. There are two notches 81, 82, in the plate 79, adapted for engagement by the dog or projection 77, and located to correspond with the raised and lowered positions of the lever, respectively. The sleeve 78 has a slot-and-pin connection with the lever, as at 84, to limit its movement thereon, and it is further attached to the outer end of the lever by means of a spiral spring 85, which normally slides the sleeve inward over the lever and presses the dog or toothed projection into engagement with either of the notches 81, 82. Either lever, it will be seen, can be easily unlocked from the retaining plate 79, by merely drawing the sleeve 78 outward against the action of the spring 85, so as to disengage the dog or toothed projection.

Having thus described my invention, what I claim, and desire to secure by Letters Patent of the United States, is:

1. The combination with a surface designed to receive vehicles and having a recess extending continuously thereacross, of a disappearing stop filling said recess, means

for positively raising said stop to place it in an elevated plane transverse to the direction of movement of the vehicles, and steadyng means pertaining to the stop operating to 5 hold it firmly positioned in said plane.

2. The combination with a surface substantially even throughout and a vehicle to be temporarily retained thereon, of a normally depressed stop for the vehicle adapted 10 to rise from said surface, an actuator for said stop, and external means moved by the stop serving to hold it edgewise in an erect position.

3. The combination with a surface open 15 for the admission of a vehicle and having recesses extending across the path thereof, of level stops overlying said recesses, mechanism for swinging out said stops in front and rear of the vehicle respectively, and 20 outwardly disposed means serving to keep the stops upright with the recesses intervening between them and the vehicle.

4. The combination with a surface intended to carry a vehicle and having a continuous recess extending transversely thereof, of a stop countersunk in said recess, means for positively raising said stop across the path of the vehicle, and abutments at the opposite ends of the stop limiting the 30 range of action of said raising means.

5. The combination with a surface open to let a vehicle pass in and out and having a space for temporarily retaining the vehicle, of a pair of stops for the latter normally reclining in front and in rear thereof, and independently operable actuating means for each stop whereby either one in said pair can be raised at option to bar the passage at the corresponding end of said 40 surface.

6. The combination with a surface open to receive a vehicle and having a transverse recess extending approximately the full width thereof, of a stop arranged to 45 lie flush with said surface within said recess, a pivotal connection at one edge of the latter permitting said stop to be turned at a substantially right angle across the path of the vehicle, an actuator for raising the 50 stop, and means adjacent to said connection operating to hold the upstanding stop with its free edge uppermost.

7. The combination with a surface adapted to receive a vehicle, of a stop in said 55 surface having a pivotal connection therewith allowing it to recline for the vehicle to pass over, and means located above the surface outside the path of the vehicle

whereby said stop can be held thereacross in an elevated position.

8. The combination with a surface designed to receive a vehicle and having a groove transverse to the path thereof, of a stop covering said groove and adapted to be swung therefrom over said surface to 65 bar the way of the vehicle, a device for swinging said stop, and means on the latter affording it a support upon the surface to resist movement of the vehicle.

9. The combination with a transversely 70 grooved surface designed to receive a vehicle, of a stop for the latter movable in and out of the groove of said surface, a lever adapted to move said stop either to raise or lower the same, and a self-locking 75 device slidable longitudinally of said lever operating to hold it fast after actuation in either direction.

10. The combination with a surface adapted to receive a vehicle and formed 80 with grooves at a distance apart approximately equal to the length of the vehicle's base, of movable stops in said grooves, and means for raising said stops transversely of said base at opposite ends, including an 85 independently operable lever for each stop, and a self-locking device on each lever slidable longitudinally thereon so as to maintain it in a predetermined position.

11. The combination with a movable 90 structure and a vehicle to be carried thereby, of disappearing stops adapted to retain the vehicle in a predetermined position on the structure, means for moving the latter, and mechanism for each stop independently 95 acting to render said means inoperative until said stop has been raised.

12. The combination with a structure designed to receive a vehicle for transferring it from one place or level to another, of 100 stops respectively adapted to be raised or lowered in the way of the vehicle prior to its entering or leaving the structure, means for moving the latter, and actuating mechanism for said stops, including a pair of 105 levers operatively connectible with said means so as to preclude movement of the structure before the stops have been properly positioned relatively to the vehicle.

In testimony whereof I have signed my 110 name to this specification, in the presence of two subscribing witnesses.

JAMES MICHAEL CUNNEEN.
